PAGE 2

FIGURE 1 is a front elevational view of a building showing my new design.

FIGURE 2 is a side elevational view thereof.

FIGURE 3 is an elevational view of the back of the building.

FIGURE 4 is a side elevational view of the side of the building opposite that shown in FIGURE 2.

FIGURE 5 is a perspective view looking down upon the roof of the building.

The dominant features of the design reside in those portions shown in solid lines, namely, the roof portions.

I claim:

The ornamental design for a building, substantially as shown and described.
